(57) **CLAIM**

The ornamental design for a building material attachment clip, as shown and described.

DESCRIPTION

FIG. 1 is a front left top perspective view of a building material attachment clip showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front right bottom perspective view thereof.

The dashed broken lines shown in the Figures represent portions of the building material attachment clip that form no part of the claimed design. The dot-dash broken lines define the bounds of the claimed design and form no part thereof.
